DRAGLINE SCRAPER

Allan T. Spencer, Jr., Gerber, Calif.

Application June 19, 1939, Serial No. 279,872

2 Claims. (Cl. 37—136)

My invention relates to means for moving material, particularly earthy material, and is concerned especially with an earth scraper and carrier of the dragline type.

5 Devices of this general character are in common use for excavating and transporting earth, and it is a general object of my invention to improve them.

It is a further object of my invention to increase the carrying capacity of a dragline scraper, especially by preventing inadvertent discharge of excavated earth therefrom.

Another object of my invention is to provide a positive opening and closing movement of the 15 earth-retaining members of a dragline scraper.

An additional object of my invention is to provide a dragline scraper which, while having positive earth-retaining capacity, can be moved into a position for complete discharge.

20 A further object of my invention is to provide a dragline scraper having a front apron which is in itself effective to excavate earth positively and to discharge earth positively.

An additional object of my invention is to provide 25 a dragline scraper in which the lines are simply arranged and maneuvered.

The foregoing and other objects are attained in the embodiment of the invention illustrated in the drawings, in which

30 Fig. 1 is a side elevation of a dragline scraper constructed in accordance with my invention, in transporting position;

Fig. 2 is a plan of the structure shown in Fig. 1;

35 Fig. 3 is a side elevation similar to Fig. 1, but showing the dragline scraper in excavating position; and

Fig. 4 is a view in side elevation showing the dragline excavator in discharging position.

40 In its preferred form, the dragline scraper of my invention includes a main bowl to which is pivoted a front apron movable by means of a crank arm, there being secured to the main bowl a hoist line and from it an apron line attached to the front apron, and there being secured to the crank arm a dragline and, branching from it, a control line which passes around a sheave secured to the hoist line and then extends to the crank arm.

50 While the dragline scraper of my invention is susceptible of various modifications, depending upon various conditions of use or preferences of the designer, it is illustrated herein in an effective embodiment for general use.

55 The excavator is adapted to be utilized to ex-

cavate earth 6 and to carry it to a discharging location, and for that purpose includes a main bowl 1, conveniently fabricated of metal and preferably including a bottom 8, a rear end wall 9, and a pair of side walls 11 and 12. To assist in dislodging and loosening the earth to be excavated, the leading edge of the bottom 8 is provided with a plurality of downwardly inclined excavating teeth 13 terminating in cutting edges 14, so that the earthy material will be cut loose from its surroundings and will slide up the incline of the teeth 13 into the main bowl 1. To assist the main bowl in excavating, and also to retain earth which has been excavated, I provide a front apron generally designated 16. This is preferably fabricated of metal and includes a bottom 17 merging with a front wall 18 and a pair of side walls 19 and 21. Extending rearwardly from the bottom 17, and designed to assist in excavating, is a plurality of cutting teeth 10 20 22 offset with respect to the forwardly projecting members 13 so that in closed position the members 13 and 22 interengage.

The front apron 16 is preferably mounted on the main bowl for pivotal movement, and for that 25 reason I provide either two short stub axles, if it is important that the main bowl be unobstructed, or, if greater rigidity is desired, a single axle 23 extending across the main bowl substantially above the cutting edge 14. The stub 30 axles or, in the present case, the single axle is rotatably mounted in upwardly extending ears 24 on the side plates 11 and 12, reinforced by additional plates if desired. Preferably, the axle 23 is fastened to ears 26 upstanding from the side 35 walls 19 and 21 of the front apron, so that the apron turns with rotation of the axle.

To provide pivotal movement, when desired, between the front apron and the main bowl, I likewise secure to each of the stub axles or to 40 the axle 23, outside of the side walls of the main bowl, a pair of crank arms 27 and 28. These are protected during excavation by arcuate guards 29 secured to the side walls 11 and 12 and extending outwardly therefrom slightly beyond the 45 crank arms in all positions thereof.

To move the dragline scraper and to control its movement, I provide a pair of lines, namely, a hoist line and a drag line, which operate generally in conjunction but which are under the separate 50 control of an operator for producing the various movements requisite and desired. The hoist line 31 includes a plurality of component parts, especially a cable 32 which is secured to a ring 33 joining a pair of chains 34 and 36 connected to 55

eyes 37 adjacent the extremities of a horizontal spreader bar 38 of substantially the same width as the main bowl 7. Depending from the eyes 37 are hoist chains 41 and 42, depending substantially parallel to the sides 11 and 12 of the main bowl and terminating in pivotal connections 43 to reinforcing ears 44 secured to the side walls at points considerably to the rear of the center of gravity of the main bowl 7.

10 For assisting in controlling the front apron 16 I preferably extend an apron line 51, such as a cable, from a fastening at one end to the ring 33 to a connection at the other end to a link 52 which itself is connected by a pivot 53 to ears 54 on the forward wall 18 of the front apron.

15 The dragline 56 includes a plurality of components, such as a cable 57 which is fastened to a link 58 on which an equalizer bar 59 is mounted by a pivot 61. From the opposite extremities of the equalizer 59 drag chains 62 and 63 extend rearwardly around the sides 19 and 21 of the front apron and terminate at their rearward ends in pivotal connections 64 to links 66 each of which is mounted on a pivot pin 67 at the lowermost 25 extremity of the adjacent one of the crank arms 28 and 29.

Also connected to the link 58 by a connector 63 is a pair of control lines 69 and 71 preferably constituted of cables, each of which extends over its 30 associated one of a pair of sheaves 72 and 73, flexibly articulated to eyes 74 and 76 adjacent the outer extremities of the bar 38. After passing around its sheave 72 or 73, each control line passes around one of a pair of idler pulleys 77 35 each mounted on a strap 78 having an offset central portion and freely pivoted on the axle 23. From its passage around the pulley 77, the control line passes around a second pulley 79 which is one of a pair journaled on ears 81 upstanding 40 from the side walls 11 and 12 of the main bowl and located just above the pivot 67 when the front apron is in closed position. The control line, after passing around the pulley 79, is connected at its extremity to the link 66 on the opposite 45 site side of the pivot pin 67 from the connection 64.

When the dragline scraper is to be propelled forwardly to excavate, the hoist line 32 is left somewhat slack and the dragline 56 is tautened. 50 This is effective to tension the control cables 69 and 71 and also to tension the drag chains 62 and 63 so that the crank arms 28 are swung forwardly, sufficient slack to provide for the forward movement of the pulleys 72 and 73 being allowed 55 in the hoist line. The forward movement of the cranks 28 and 29 rotates the apron 16 into its open position, substantially as shown in Fig. 3, so that the tension of the drag cable 57 is exerted through the crank arms and through the control lines 69 and 71 at a point substantially at the center of gravity or slightly above or below it, the precise design in any case depending upon the desired digging characteristics of the cutting edge 14.

60 When substantially a full load has been gathered into the main bowl, the hoist line 32 is tautened while the dragline 56 is somewhat slackened,

and this change in forces moves the dragline 32 to maintain or even increase the tension upon the control lines 69 and 71 while permitting the drag chains 62 and 63 to slacken if necessary, at least until the crank arms 28 are moved from their 5 apron-open position, as shown in Fig. 3, into their apron-closed position, as shown in Fig. 1. This closing movement of the front apron is therefore effected positively so that the descending cutters 22 of the apron bottom 17 are in themselves effective to cut through some of the earth 6 and to load additional material not only into the main bowl but also into the front apron, the effect of the two parts of the dragline scraper being in this respect similar to that of a clam shell bucket.

With an appropriate ratio between the tensions on the hoist line 32 and the dragline 56, exerted not so much through the drag chains 62 and 63 as through the control lines 69 and 71, the dragline scraper is transported in substantially its position as shown in Fig. 1, from the excavating location to a discharging location. At the discharging location the drag line 56 is left somewhat slack, so that substantially the entire weight of the structure comes upon the hoist line 32. Since the points of connection 43 of the hoist line to the main bowl are considerably to the rear of the center of gravity thereof, the weight of the structure, as well as its contained load, is effective to move the parts substantially to the discharging position shown in Fig. 4, the effect of the control lines 69 and 71 during such movement being to urge a positive and full opening of the front apron 16. But since the lines 62 and 63 may sometimes be somewhat slack, the line 51 is always effective to cause the front apron and the main bowl to move to a relatively open position, since, even without the line 51, the entire weight of the structure and its load is borne upon 40 the lines 41 and 42 and upon the line 51 with an articulation therebetween so that the entire weight is effective to induce an opening or dumping movement.

After discharge, a lessening of the force on the 45 hoist line 32 and an increase thereof on the dragline 56, especially if the scraper is deposited upon the ground, restores the parts to excavating relationship, as shown in Fig. 3.

I claim:

1. A dragline scraper comprising a main bowl, a front apron pivoted thereon, a crank arm for pivoting said front apron overlying the side of said main bowl, means for moving said crank arm to sweep over said bowl side, and an arcuate guide outstanding from said bowl side beyond the end of said crank arm.

2. A dragline scraper comprising a main bowl having sides, a front apron disposed between said sides and pivoted thereon, a pair of crank arms secured to said front apron and externally overlying said sides, means for moving said crank arms for pivoting said front apron, and external guards on said sides adjacent the ends of said crank arms.
